UNITED STATES PATENT OFFICE.

JAMES M. O'KELLY, OF NEW YORK, N. Y.

PASSENGER-RECORDER FOR PUBLIC VEHICLES.

SPECIFICATION forming part of Letters Patent No. 478,016, dated June 28, 1892.

Application filed March 16, 1891. Serial No. 385,159. (No model.)

To all whom it may concern:

Be it known that I, JAMES M. O'KELLY, a citizen of the United States, residing at New York, N. Y., have invented a new and useful 5 Passenger-Recorder for Public Vehicles, of which the following is a specification.

My invention is designed as an appendage to tram and railway cars, having for its object the automatic recording of the occupancy 10 of each seat.

In the accompanying drawings, which form a part of this specification, Figure I is a partly-sectioned elevation of a seat and connected recording mechanism. Fig. II is an elevation 15 at right angles to Fig. I. Fig. III is a fragmentary elevation, and Fig. IV is a plan of the recording device proper.

1 may represent part of a car-floor, and 2 the supporting frame or standard of a seat or 20 range of seats 3. Each seat is supported on a fulcrum 4, transverse of the seat, so that on said seat being occupied by a passenger it will tip either forward or backward.

4' represents a plumb, which operates to 25 restore the seat 4 to its normal position.

5 are levers pivoted to the seat at 6 and resting on fulerums 7, so that on said seat being tipped or depressed, as aforesaid, one or other rod will assume the position indicated 30 by dotted lines in Fig. I in such a way as to draw or pull a cord 8, which, being rove around sheaves 9, is conducted upward along a post 10 and attached to the shorter limb 11 of a bent lever 11 12, whose longer limb 12 carries 35 a pencil 13. A spring 14 operates to normally hold the pencil to its retracted and inoperative position (shown in Fig. I) at all times, except when acted on by depression of the seat, with which it is connected. Each seat is

equipped with such a recording pencil or 40 stylus and operative connection.

15 is a tablet fixed at a convenient part of the car.

16 is a paper strip or blank whose face is marked off with horizontal columns—one for 45 each seat—and vertical columns having hour-marks. This strip is wound upon a spool 17 and has one end of it carried forward between guides 18 in front of and parallel to the tablet to a drum 19, that is driven by connection 50 of cog-wheel 20 with suitable clock-work 21.

The above-described form of my invention may be modified as follows: 13 may represent a steel stylus, and 16, Fig. III, a sheet of paper coated with some transferring-pigment 55 (such as a carbon or an aniline paste) to be fastened in front of the tablet 15, Fig. IV, and renewed as often as may become necessary. The seat may be arranged to operate by descending bodily instead of by the above-described rocking or tipping action.

In practice the recorder will be located in a locked closet, accessible only to one in possession of a special key.

Having thus described my invention, the 65 following is what I claim as new therein and desire to secure by Letters Patent:

In a passenger-recording device, the combination of compressible seat 3, levers 5, cord 8, pencil-holder 11 12, spring 14, tablet 15, strip or blank 16, spool 17, drum 19, cog-gearing 70 20, and clock mechanism 21, all arranged substantially as and for the purposes set forth.

JAS. M. O'KELLY.
